DESIGN FOR APPLIQUE EMBLEM OR THE LIKE

Charles N. Maybruck, Forest Hills, Long Island,
N. Y.

Application July 24, 1941, Serial No. 102,455

Term of patent 3½ years

To all whom it may concern:

Be it known that I, Charles N. Maybruck, a citizen of the United States, residing at Forest Hills, Long Island, in the county of Queens and State of New York, and whose post-office address is 7540 Austin Street, Forest Hills, Long Island, New York, have invented a new, original, and ornamental Design for Applique Emblem or the like, of which the following is a specification, reference being made to the accompanying drawing, forming a part thereof, in which:

Fig. 1 is a front view of an applique emblem showing my new design.

Fig. 2 is a bottom edge view thereof.

I claim:

The ornamental design for applique emblem or the like, substantially as shown.

CHARLES N. MAYBRUCK.
